UNITED STATES PATENT OFFICE.

JOSEPH H. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY.

BACK GAUGE FOR NAILING MACHINES.

Application filed September 6, 1923. Serial No. 661,222.

To all whom it may concern:

Be it known that I, JOSEPH H. POPE, a citizen of the United States, residing at Hamilton, in the county of Essex and State 5 of Massachusetts, have invented certain Improvements in Back Gauges for Nailing Machines, of which the following description, in connection with the accompanying drawings, is a specification, like reference characters 10 on the drawings indicating like parts in the several figures.

My invention relates to back gauges for nailing machines, as those which locate a shoe-upper in correct relation to a heel 15 which is to be attached to the heel-seat by nailing.

Objects of the invention are to furnish such a gauge which is freely adjustable to insure proper positioning of the work under 20 all conditions, this including, if desired, plural vertical adjustments and transverse adjustments in a plurality of directions; which may be movable in the operation of the nailing machine without interference 25 with the adjustments; and which will provide at all times a firm stop to receive the contact of the work.

One of the several embodiments which the invention may assume is illustrated in the 30 accompanying drawing,

Fig. 1 being a front elevation of a portion of a nailing machine including my improved gauge;

Fig. 2 an enlarged front elevation of the 35 gauge device;

Fig. 3 a side elevation thereof with parts broken away; and

Fig. 4 a top plan view of the gauge.

At 10 in Fig. 1 appears the frame of a 40 Lightning nailing or heel-attaching machine of the character of that described in Patent No. 446,885, dated February 24, 1891. This frame supports a die-block 12, with the openings of which cooperate reciprocating 45 drivers 14, and having movable toward and from its under side a jack 16 mounted upon a reciprocating cross-head 18. Rising from the cross-head is a supporting bracket 20 furnishing one portion of a hinge, the oscillatory leaf of which appears at 22. At the 50 rear of the leaf-portion of the hinge are vertical ways 24 to receive a carrier-bar 26, the inclined edges 28 of which conform to the ways. The portion 22 is divided at 30, and 55 the opposite sections may be drawn together

to clamp the bar 26 against movement between them by a screw 32 turning loosely in one of the sections of the leaf and being threaded into the adjacent section. With the screw loosened, the bar may be moved 60 vertically to the desired position, and there clamped in place by tightening the screw to draw the sections into engagement with the bar. If, for any reason, as to effect repairs, it is desired to remove the cross-head 18, the 65 bar 26, with the elements which it carries, may be entirely withdrawn from the supporting leaf. This avoids interference by the gauge device with the removal of the cross-head, through its contact with the die-block. 70

Secured to the frame at the rear of the jack is a bracket 34 having a horizontal opening to receive a screw 36 extending transversely of the bar 26. This screw may 75 be advanced or withdrawn through the bracket by a nut 38 which is situated between separated portions of the bracket. Hinged at 40 to the forward extremity of the screw 36 is a plate 42 provided with inclined edges 44 to fit ways 46, formed along the rear side of the bar 26 and near its opposite edges. This sliding connection between the bar and the adjusting screw 36 permits the free reciprocation of the former 80 as the cross-head 18 rises and falls in the operation of the machine, there being, however, always maintained the adjusting connection between the screw and the bar. 85

Upon the upper portion of the bar 26 is 90 a slide 48 having, at its opposite sides, ways 50 for co-operation with the inclined edges 28 of the bar. The slide is divided at 52, and is provided with a screw 54 for drawing the portions together to clamp the slide 95 upon the bar at whatever point it may be adjusted, this operating in the same manner as does the clamping screw 32. Extending transversely of the front face of the slide near its upper extremity are dovetailed ways 56 to receive a block 58. Projecting from the top of this block forwardly, and here shown as somewhat inclined upwardly, is a gauge member or back stop in the form of a fork 60. The divergence between the arms of the fork is such that the gauge is adapted to contact with the opposite sides of the counter portion of the shoe carried upon the jack 16, this contact being at separated points just forward of 110

the rear of the counter. Its upward inclination adapts it for use with women's shoes of the Spanish or high-arch type. In these the heel-seat of a jacked shoe lies, with respect to the horizontal, at a considerable upward angle toward the front of the machine. My inclined fork readily engages the counter of such a shoe, without interference with the heel or rand. Threaded through the block is a screw 62, upon the opposite ends of which are fixed heads 64, 64. The inner adjacent faces of these heads bear against the edges of the slide 48, thus holding the screw against longitudinal movement. When it is turned, it causes the travel of the block 58 in its ways and thus shifts the fork 56 transversely of the jack. In using this gauge device, the fork 60 is adjusted by the screw 62 until it is centralized with respect to the jack, this permitting a correction for wear of the moving parts and for defects in manufacture. By varying the position of the bar 26 in the hinge-portion 22 or the slide 48 upon the plate 42, the fork may be positioned vertically so it is arranged to most effectively contact with the counter-portion of the jacked shoe for the particular height of last employed, the double adjustment giving wide range of movement and that controlled by the screw 32 being readily accessible to the operator after the jack has been thrust into nailing position. As already pointed out, the capability for complete separation of the gauge device at the clamp holding the bar 26 facilitates the removal of the cross-head 18. The location of the jacked shoe from front to rear of the die-block to bring the heel-seat into correct relation with a heel H which is to be attached, is provided for by rotation of the nut 38, this changing the position of the screw 36 and therefore of the fork. The adjusting connection between the screw 36 and the gauge is maintained in all positions of the cross-head without interference with the movement of the latter, by means of the sliding of the plate 42 and by the pivotal connections. These connections, being furnished by the hinges at 22 and 40, which may be made entirely free from lateral play, insure a positive location of the gauge without displacement when the work is moved against them.

Having described my invention, what I claim as new and desire to secure by Letters Patent of the United States is:

1. A back gauge for nailing machines comprising a support, a carrier extending from the support and pivotally connected thereto, a gauge member mounted upon the carrier, and an adjusting member movable transversely of and pivotally connected to the carrier.

2. A back gauge for nailing machines

comprising a support, a hinge-leaf pivoted thereon, a bar secured to the leaf, a gauge mounted upon the bar, an adjusting member movable transversely of the bar, and a hinge-connection between the adjusting member and the bar.

3. A back gauge for nailing machines comprising a support, a hinge-leaf pivoted thereon, a bar secured to the leaf, a screw having its axis extending transversely of the bar, a member fixed relatively to the bar and into which the screw is threaded, and a hinge-connection between the screw and bar.

4. The combination with a frame, of a support movable thereon, a carrier hinged to the support, a gauge member mounted upon the carrier, an adjusting member movable upon the frame, and a hinge joining the adjusting member and carrier and having sliding connection with said carrier.

5. The combination with a frame, of a cross-head movable thereon, a bar pivotally mounted upon the cross-head, a gauge member mounted upon the bar, a screw movable upon the frame, and a member pivoted upon the screw and having sliding engagement with the bar.

6. A back gauge for nailing machines comprising a support, a carrier movable upon the support, means for securing the carrier against such movement, a slide movable upon the carrier, means for fixing the slide in position, and a gauge member mounted upon the slide.

7. A back gauge for nailing machines comprising a support, a hinge-leaf pivoted thereon, a bar arranged to slide longitudinally of the leaf, means for securing the bar against movement, adjusting means pivoted to the bar, a slide movable along the bar, means for fixing the slide in position, and a gauge member mounted upon the slide.

8. A back gauge for nailing machines comprising a support, a carrier extending from the support and pivotally connected thereto, a gauge member movable transversely of the carrier, and means arranged to vary the position of the gauge member.

9. A back gauge for nailing machines comprising a support, a bar pivoted upon the support, a slide movable along the bar, and a gauge member movable transversely of the slide.

10. A back gauge for nailing machines comprising a support, a bar pivoted upon the support, a slide movable along the bar, means for fixing the slide in position, a gauge member movable transversely of the slide, and a screw threaded into the gauge member and contacting with the slide.

In testimony whereof I have signed my name to this specification.

JOSEPH H. POPE.
